UNITED STATES PATENT OFFICE.

CEPHAS V. FITE AND HENRY K. BARWICK, JR., OF CHARLOTTE, NORTH CAROLINA.

COMBINATION-LOCK VALVE.

1,174,061.

Specification of Letters Patent. Patented Mar. 7, 1916.

Application filed June 30, 1915. Serial No. 37,303.

To all whom it may concern:

Be it known that we, CEPHAS V. FITE and HENRY K. BARWICK, Jr., citizens of the United States, residing at Charlotte, in the county of Mecklenburg, State of North Carolina, have invented a new and useful Combination-Lock Valve, of which the following is a specification.

This invention relates to a valve especially designed for use in controlling the supply of gasoline to the carburetor of a hydro-carbon motor such as used in automobiles, motor boats, motorcycles and the like.

One of the objects of the invention is to provide a valve made up of relatively movable sections constituting tumblers of a combination lock, the said sections or tumblers having coöperating means whereby, by the manipulation of a knob or stem, openings within the tumblers or sections will be brought into register and thus permit the passage of liquid through the valve from the inlet to the outlet. When, however, any one of these tumblers is out of registration, the passage of liquid through the valve will be cut off and can only be effected by manipulating the device to bring the various tumblers into a predetermined relation.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

40 In the accompanying drawing, the preferred form of the invention has been shown.

In said drawing:—Figure 1 is a central vertical section through the valve, the tumblers being shown in position to permit the passage of fluid through the valve. Fig. 2 is a face view of the valve operating knob and the dial plate adjacent thereto. Fig. 3 is a section on line A—B Fig. 1. Fig. 4 is a section on line C—D Fig. 1.

45 Referring to the figures by characters of reference 1 designates a cylindrical casing provided in one end with an outlet port 2 and adjacent its other end with an inlet port 3. A valve stem 4 is mounted for rotation within the casing and may be rotated in any suitable manner, as by means of a knob 5,

there being a dial 6 adjacent the knob having any desired arrangement of characters thereon to guide the user in manipulating the valve.

60 The casing 1 is concentric with the stem and fitting snugly within the casing is a series of tumblers 7 and 8, each of these tumblers being in the form of a disk provided in its periphery with recesses 9. Each 65 recess has a shoe 10 movably mounted therein and normally pressed against the inner surface of the wall of the casing 1 by a spring 11. These shoes by frictionally engaging the wall of the casing serve to retard 70 the rotation of the tumblers within the casing.

75 The lowermost tumbler 7 is formed with recesses 12 adapted to receive the ends of a pin 13 extending through one end portion 80 of the stem 4 so that, when the stem is rotated, the tumbler 7 will be likewise rotated. This tumbler has a circular series of recesses 15 in one face any one of which is adapted to receive a pin 16. Said pin projects into 85 a circular groove 17 formed in the adjacent face of the next adjoining tumbler 8 and the inner wall of this circular groove has a pin 18 projecting therefrom and adapted to engage the pin 16 during the relative movement of the two tumblers 7 and 8.

90 Formed in that face of the tumbler 8 remote from the groove 17 is a circular series of recesses 19 any one of which is adapted to receive a pin 20 similar to the pin 18 and 95 which projects into the groove 17 of the next adjoining tumbler 8. The uppermost tumbler 8 is not provided with a pin 20 but is, instead, engaged by one end of a coiled spring 21 which is mounted on the stem 4 100 and bears against the end of the casing 1. This spring 21 serves to hold several tumblers pressed tightly together. The port 3 enters into the casing 1 between the innermost tumbler 8 and the adjacent end of the 105 casing 1.

110 Each of the tumblers 7 and 8 has an opening 22 extending entirely through it and these openings are all so located that when the various tumblers are brought to predetermined positions relative to each other the openings 22 in the different tumblers will register with each other and with the outlet port 2, thus establishing communication between the ports 2 and 3.

It will be apparent that by connecting a supply tank or reservoir to the port 3 and

2 by extending a feed pipe from the port 2 to the carbureter or other point of consumption, the communication between the supply and the port 2 can be cut off simply by turning one or more of the tumblers 7 and 8 by means of the stem 4. Before the fuel can be permitted to pass to the port 2, it will be necessary to so manipulate the tumblers by means of the stem 4, as to bring the different open 10 igs into register with each other and with the port 2.

The device constituting the present invention is very simple, durable and efficient and by reason of its compact construction, can 15 be readily placed in position upon a motorcycle, automobile or the like.

What is claimed is:—

1. A valve including a casing having an outlet in one end and an inlet adjacent its other end, circular tumblers mounted for rotation within and fitted snugly against the wall of the casing, said tumblers having openings extending therethrough and adapted to be brought into register with the outlet to form a straight outlet passage through the tumblers to the outlet, there being a space between the tumblers and the inlet end of the casing, an element for manipulating all of the tumblers and extending through the centers of the tumblers and beyond one end of the casing, coöperating means on the tumblers for moving the tumblers successively in accordance with a predetermined combination to bring the openings into registration, and yielding means housed within the space in the casing and holding all of the tumblers pressed yieldingly together and against the outlet end of the casing.

Copies of this patent may be obtained for five cents each, by addressing the "Commissioner of Patents, Washington, D. C."

2. A valve including a casing having an outlet in one end and an inlet adjacent its other end, circular tumblers mounted for rotation within and fitted snugly against the wall of the casing, said tumblers having openings extending therethrough and adapted to be brought into register with the outlet to form a straight outlet passage through the tumblers to the outlet, there being a space between the tumblers and the inlet end of the casing, an element for manipulating all of the tumblers and extending through the centers of the tumblers and beyond one end of the casing, adjustable coöperating means on the tumblers for moving the tumblers successively in accordance with a predetermined combination to bring the openings into registration, yielding means housed within the space in the casing and holding all of the tumblers pressed yieldingly together and against the outlet end of the casing, and spring pressed radially movable means in each tumbler for slidably engaging the casing.

In testimony that we claim the foregoing as our own, we have hereto affixed our signatures in the presence of two witnesses.
